VARIABLE ALARM

Albert G. Thomas, Lynchburg, Va.

Application April 6, 1935, Serial No. 14,986

6 Claims. (Cl. 116—149)

The present invention relates to the subject matter of application Serial Number 758,948, filed Dec. 24, 1934 and shows further variations in design to accomplish the same general result, that is to devise alarms that will begin with soft signals and which will become louder after a period of time.

An alarm that starts gently and then becomes louder is very desirable since it will not startle the sleeper as often happens with ordinary alarm clocks when loud alarms suddenly begin.

The principal object of this invention is to provide an alarm that may be incorporated in an alarm clock so that an alarm signal of varied strength or of varied character may be produced.

Another object is to provide an alarm that will be automatically set to soft signal position when the manual alarm lock is manipulated, so that when the time gears of the clock allow the alarm to sound, the signals will always be soft for an initial period.

A further object is to design variable alarm mechanism that can be economically incorporated in clocks as now made, with few changes.

Other objects will appear in the following description:

In the drawings:

Figure 1 is a side elevation of an alarm, the hammer of which is actuated by a toothed wheel. Figure 2 is a plan view of the construction shown in Figure 1.

Figure 3 is a side elevation, in part section, of an alarm in which the hammer is damped by a piston and cylinder.

Figure 4 is a side elevation of an alarm in which the toothed wheel actuating the hammer is adjustable with respect to the hammer arm.

Figure 5 is a side elevation of an alarm in which the speed of vibration of the hammer is varied by a movable weight sliding on the hammer arm.

Figure 6 is a side elevation, in part section, of an alarm with a soft hammer and a hard hammer.

Figure 7 is a fragmentary side elevation of an alarm that is automatically set to soft position when the alarm is locked.

Figure 8 is a side elevation of an alarm in which the speed of vibration of the hammer is regulated by an air fan which is thrown out of gear to produce faster vibrations.

Figure 9 is a side elevation of an alarm with a soft bell and a loud bell.

Figure 10 is a side elevation of an alarm with a loud bell and a soft bell pivoted so that either may be brought into contact with the hammer.

Figure 11 is a side elevation of an alarm in which the rate of vibration of the hammer is determined by a centrifugal frictional governor.

Figure 11A is a front elevation of the verge and hammer construction of Figure 11.

Figure 12 is a fragmentary side elevation of an alarm in which the inertia effect of weights is used to control the speed of vibration of the hammer. 5

Figure 13 is a fragmentary side elevation of an alarm in which the speed of vibration of the hammer is determined by a sliding weight on the hammer arm. 10

Figure 14 is a fragmentary side elevation of an alarm in which the speed of vibration of the hammer is increased by lifting a weight from the hammer arm.

Figure 15 is a fragmentary side elevation, in 15 part section, of an alarm in which the rate of vibration of the hammer is regulated by friction.

Figure 16 is a plan view of a hammer arm regulated by friction.

Figure 17 is a fragmentary elevation of an 20 alarm which is easily attached to ordinary alarm clocks. The amplitude of vibration of the hammer is regulated.

Figure 18 is a side view of a detail of Figure 17.

Figure 19 is a schematic diagram of a variable 25 alarm suitable for electric clocks.

Figure 20 is a fragmentary side section of a detail of Figure 19.

Figure 21 is a rear elevation of the alarm set disc of Figure 20. 30

Figure 22 is a back view of another alarm regulated by a piston and cylinder.

Figure 23 is a fragmentary back view of an alarm regulated by a piston and cylinder, the piston being linked to a gear. 35

Figure 24 is a back view of an alarm which is varied by rotating a pivoted gong with reference to the hammer.

In Figures 1 and 2, hammer 1, adapted to strike bell 2, is fastened to hammer arm 3 which has 40 bent arm 4 normally resting on the peripheral surface of toothed wheel 5 which is rotatable on key shaft 6. Hammer arm 3 is pivoted to clock frame 8 at 7 and has arm 10 extending beyond the pivot so that pin 11 on locking rod 12 will depress arm 10 and therefore lift arm 4 above teeth 16 when rod 12 is depressed to lock the alarm mechanism. Coiled spring 9 normally presses arm 4 against toothed wheel 5. 45

Locking is accomplished by finger 14 of spring 50 arm 13, which is attached to rod 12, falling into notch 15 on the periphery of sleeve 21. Therefore toothed wheel 5 will always be stopped in the same position so that when the alarm is released by the timing gears small teeth 17, widely spaced, will first lift arm 4 and allow it to fall thereby causing hammer 1 to strike bell 2 a succession of weak blows. As wheel 5 rotates, large teeth 16 then lift arm 4 and cause hammer 1 to strike harder blows. The large teeth 16 may be 55 60

spaced closer together than small teeth 17 so that in addition to being louder, the signals produced will be more frequent. The back sides of teeth 16 are approximately radial so that arm 4 will fall off suddenly and produce sharp blows. Likewise hammer 4 is normally held slightly away from bell 2 so that the hammer 4 will strike bell 2 and then bounce away to prevent damping.

Toothed wheel 5 and gear 22 are fastened to sleeve 21 which is rotatable on key shaft 6, being driven by ratchet 27 when spring 18 unwinds. Shaft 6 has bearing in clock frame 8 and may be turned by key 28 to rewind spring 18 since arm 4 is lifted above teeth 16 when locking rod 12 is depressed.

Gears 19 and 23 are fastened to shaft 24 and gear 25, meshing with gear 19, is fastened to shaft 26 to which is also fastened fan 20 which, when rotating, regulates the speed of rotation of toothed wheel 5.

Therefore this alarm will first produce a series of soft signals and then loud signals.

In Figure 3 rocker 29 is vibrated by the usual toothed wheel 30 which is rotated by spring 25 driven key shaft 32 in conjunction with gear 31 fixed to rotatable shaft 32; gear 33 fixed to rotatable shaft 35; and gear 34 fixed to shaft 36 to which is fixed toothed wheel 30.

Link 40 is pivoted to hammer arm 37 at 39 and to piston 42 at 41 so that vibration of hammer arm 37 reciprocates piston 42 in cylinder 43 in arm 37 which is rotated by shaft 35. Spring 46a, attached to arm 45 and frame 49, normally keeps valve 44 closed so that air will be compressed in cylinder 43 and will leak out of small hole 50 so that the rate of vibration of hammer arm 37 will be slow, resulting in a series of infrequent gentle taps of hammer 38 on bell 48. But when shaft 35 has been rotated through a sufficient angle to cause cam 47 to strike arm 46 and lift valve 44 the resistance to movement of piston 42 will be largely eliminated and the rate of vibration and the strength of blows struck by hammer 38 will increase so that loud alarm signals will result.

In Figure 4 the general principle is the same as shown in Figures 1 and 2 except that toothed wheel 51 has teeth of uniform length and the variation in tone of bell 52 when struck by hammer 53 is achieved by lifting wheel 51 vertically, with respect to pivot 56, to lift hammer 53 away from bell 52 and therefore to produce weak signals when toothed wheel 51 is rotated and strikes arm 54 attached to hammer arm 55. Spring 57 normally holds arm 54 against wheel 51.

When toothed wheel 51 is lowered, hammer 53 is brought nearer to bell 52 so that the signals will be louder. Toothed wheel 51 is fastened to shaft 58 which has bearing in support 59, a branch of which is pivoted to the clock frame at 60. Cam 61 is fastened to key shaft 62 which also has bearing in support 59. Gear 63 is fastened to shaft 58 and gear 64, meshing with gear 63, is fastened to key shaft 62. Fastened to fan shaft 67 is gear 65 which meshes with gear 64 so that fan 66 will regulate the speed of rotation of toothed wheel 51.

Post 68 is fixed to clock frame 70 and spring 69, fastened to support 59 and frame 70, pulls support 59 down against stop pin 71 except when cam 61 strikes against post 68 and lifts support

59 which in turn lifts rotating toothed wheel 51 to produce soft signals. When cam 61 has been turned so that it does not strike post 68, support 59 rests against stop pin 71 and toothed wheel 51 is lowered to produce loud signals. When the driving spring is fully wound cam 61 is in position to strike against post 68 so that low signals will result first.

In Figure 5 the rate of vibration and strength of blow of hammer 72 on bell 73 is varied by varying the position of flanged weight 74 which is slidable on hammer arm 76. Yoke 75 attached to arm 77 serves to move weight 74 and at the same time allows vertical vibration of this weight. Arm 77 is attached to threaded sleeve 78 which is moved horizontally from left to right when alarm spring 80 is allowed to rotate shaft 79. Yoke 75 prevents rotary movement of sleeve 78.

The threads on key shaft 79 are cut off near the right end to leave smooth portion 81 so that sleeve 78 can run off the threads and reach a limiting position. In this way a loud alarm will be continuously sounded after weight 74 is carried to its nearest position relative to pivot 84. When spring 80 is fully wound, weight 74 will be near hammer 72 and therefore the rate of vibration of hammer 72 will be slow but when weight 74 is near pivot 84 the lever arm is less and the rate of vibration will be much faster and the blows will be stronger.

Spring 82, resting against frame 83, serves to force sleeve 78 back on the threads of shaft 79 when spring 80 is being rewound. A clutch arrangement could of course be used as indicated in previous drawings.

Toothed wheel 85 is rotated by attached gear 86 and spiral gear 87. Ratchet 88 is provided as usual so that spring 80 may be rewound without rotating toothed wheel 85.

Figure 6 shows a construction in which two hammers are used, one a soft hammer 89 and the other a hard hammer 90. Hammer 89 may be covered with leather or some soft material.

Hammers 89 and 90 are pivoted on rod 103 fastened to frame 105 and are actuated by toothed wheels 92 and 93 respectively, which in turn are rotated by gears 94 and 95. Gears 98 and 97 are fastened to sleeve 99 which is keyed to shaft 101 so that when the alarm first begins gear 98 will be in mesh with gear 94 to vibrate hammer 89 to create a soft alarm signal. As shaft 101 is rotated by spring 105 through ratchet 107, wedge 100, attached to gear 97, strikes post 104 on frame 105 and forces sleeve 99 to the left thus bringing gear 97 into mesh with gear 95 to vibrate loud hammer 90 and forcing gear 98 out of mesh with gear 94 after gears 97 and 95 have begun to mesh. Gear 98 may of course be left in mesh if desired. Spring 102 tends to force sleeve 99 toward the right. It will be seen therefore that soft hammer 89 will first strike bell 91 and then loud hammer 90.

In Figure 7 the speed of vibration of hammer 108 is regulated in a similar manner to that of Figure 5 except that sliding weight 109 is moved by pin 111 on arm 112 which is pivoted to the clock frame at 113. Stops 114 and 115 are fastened on hammer arm 110 which is actuated by toothed wheel 116 as usual.

Bent arm 118 is frictionally connected to key shaft 119 so that when shaft 119 is rotated by the alarm spring, in a clockwise direction, arm 118 strikes weight 109 and pushes it over hump 120 in hammer arm 110 so that it slides down against stop 115. Then the speed of vibration of hammer

108 will increase. Arm 118 will rotate until it strikes pin 117 on arm 112 but shaft 119 will continue to revolve to vibrate hammer 108, since there is a slip connection between shaft 119 and 5 arm 118.

When it is desired to cut off the alarm, pivoted arm 112 is rotated to the dotted position and in doing so pin 111 forces weight 109 back to the position shown and presses down against hump 10 120 to lock the hammer and alarm mechanism against further movement. At the same time pin 117 forces arm 118 back to the position shown in 15 solid lines so that the alarm is automatically reset to soft signal position when the alarm is locked. Hammer 108 strikes bell 121 a series of 20 soft blows at slow speed before arm 118 forces weight 109 over hump 120 to produce loud signals. When the alarm is unlocked arm 112 is in the 25 position shown in solid lines. The time gears of the clock release the alarm at the proper time as usual. A desirable feature of this alarm is that it is automatically set to soft position when the 30 alarm is locked.

In Figure 8 a combination fan, governor and 35 toothed wheel actuated hammer construction is used. Hammer 123 is driven by spring 124a through gear 125 and ratchet 126 and gear 127 and toothed wheel 128. Gear 122 is slidably keyed to key shaft 129, part of which is threaded. Spring 40 130 normally forces gear 122 in mesh with gear 123a which serves to rotate fan 124 but when threaded sleeve 125a is carried by rotating shaft 129 sufficiently far to the left to press gear 122 out of mesh with gear 123a the resisting effect of 45 fan 124 is eliminated and the rate of vibration of hammer 123 increases. Sleeve 125a is keyed to frame 126a to prevent rotation. In Figure 9 hammer 131 is moved from soft bell 132 to loud bell 133 by means of yoke 136 attached to traveling threaded sleeve 137. Bent arm 135 is attached to wide escapement 134 which slides across toothed wheel 138 to bring hammer 131 into alignment with bell 133. Therefore when key shaft 137a is wound hammer 131 will be opposite soft bell 132 and after a period of rotation of key shaft 137a, hammer 131 will be shifted to loud bell 133.

In Figure 10 soft bell 139 and loud bell 140 are fastened to the arms of U-shaped support 141 50 which is pivoted at 142 so that cam 143 and key shaft 144 can rock bell 140 toward hammer 145 to produce a loud tone. Bell 139 may be covered with soft material and is normally held near hammer 145 by spring 146, stop 147 being provided.

In Figure 11 the rate of vibration of hammer 55 148 is regulated by fly ball governor plate 149 rubbing against friction strip 150 which is attached to threaded sleeve 151 which moves horizontally as threaded key shaft 152 is rotated. Hammer 148 is driven by gear 153 on key shaft 152 in usual manner. Pinion gear 154 is also 60 meshed with gear 153 and drives gear 155 which in turn rotates pinion 156 which is freely rotatable on shaft 152 but which is held in lateral position by shoulder 157, and collar 158 attached to shaft 152 and rubbing against disc 159 which is fastened to pinion 156 and rotates with it. Fly 65 balls 160 are attached to the pivoted links 161 connecting laterally, and rotatably movable disc 149 which is pulled to the left against compression spring 162 when gear 156 is rotated. Therefore the further left that friction strip 150 is, the faster the fly balls must be rotated in order 70 to reach equilibrium. Therefore if key shaft 152 75 is turned to wind spring 163, threaded sleeve

151 will be moved to the right until strip 150 is close to disc 149, when spring 163 is fully wound. Key 164 working in a slot in sleeve 151 prevents rotation of that sleeve. Hammer 148 is driven by gear 153 and gears 153a, 153b, and toothed wheel 153c. The verge 153d attached to hammer arm 148a which is pivoted in the frame 148c by shaft 148b resting in suitable bearings, is rocked back and forth by rotating toothed wheel 153c to vibrate hammer arm 148a in well-known manner. Shaft 148b is fastened to hammer arm 148a or to verge 153d.

In Figure 13 the principle involved is the same as in Figure 7 except that slidable weight 169 is held in position by catch 170 which is pivoted to straight inclined hammer arm 171. The alarm signals will therefore be given slowly until cam 172 is rotated by the alarm mechanism sufficiently to strike catch 170 and release weight 169 which will slide down hammer arm 171 and so reduce the effective lever arm that the rate of vibration will be greatly increased. An advantage of this construction is that the alarm continues loud after the initial soft period, without a slipping clutch arrangement. Pivoted locking arm 173 moves weight 169 back so that catch 170 holds it again, when the alarm is locked.

In Figure 14 is shown a design in which suitably guided weight 188 may be allowed to rest on hammer arm 190 and oscillate with it to reduce its rate of vibration or it may be lifted off by cam 194 and held above it by pivoted catch 189. Slot 195 in weight 188 is provided so that the hammer movement will not be impeded when catch 189 is holding weight 188 in raised position. Cam 194 is rotated by the alarm spring and associated mechanism so that weight 188 will be lifted after a period of time. Lock bar 191 has lug 192 which strikes hammer arm 190 when the bar is depressed and lug 193 which strikes catch 189 and releases weight 188 so that the alarm will always start with slow soft signals.

In Figure 15 projection 196 on the hammer arm is rubbed by friction face 197 of sleeve 198 when catch 199 is lifted by wedge 200 on the locking rod 201 striking pivoted arm 202. Sleeve 197 is slidable on rod 206 and lock arm 201a stops vibration of hammer 196 when rod 201 is lifted. Spring 203 then presses face 197 against face 196 so that friction will slow down the rate of vibration of hammer 204. When cam 205 rotates through a sufficient angle it forces sleeve 197 to the right so that it is held by catch 199 and therefore the rate of vibration of hammer 204 will increase.

In Figure 16 hammer 207 is vibrated in the usual manner to strike bell 208. Friction pad 209 mounted to rotate with shaft 210, which is rotated by the key shaft, rubs against hammer 207 or some part of the hammer mechanism and reduces the rate of vibration for a time. This reduction is arranged to take place immediately after the alarm is released by the time gears and then pad 209 is rotated out of the way so that hammer 207 strikes bell 209 harder and faster 65 70 75 blows.

Figures 17 and 18 show a variable alarm that can be adapted to ordinary alarm clocks, with few changes in the usual alarm mechanism. Hammer arm 211 is fastened as usual to rocker or verge 214 to which is fastened shaft 212 which has suitable bearing in clock frame 213, being prevented from lateral movement by suitable collars or pins.

Toothed wheel 215, fastened to shaft 216, is 75

driven by pinion 222 which meshes with gear 223 which is fastened to rotatable shaft 228a. All of these shafts have bearing in some part of frame 213. Fastened to shaft 228a is pinion 224 which meshes with gear 225 which is loosely mounted on key shaft 228 and is rotated with this shaft, through ratchet 226, when spring 227 is allowed to rotate shaft 228. When, however, spring 227 is rewound by means of key 230, ratchet 226 allows shaft 228 to be rotated without turning gear 225 and the hammer mechanism.

It is desirable to have a high gear ratio between key shaft 228 and shaft 216 so that hammer 231 will be vibrated more slowly by the spring 227. In this way the vibration noise of verge 214 and toothed wheel 215, when bell 232 is not being struck by hammer 231, will not be excessive. A further reduction in this buzzing noise, which is for the low alarm, can be obtained by placing rubber cushions between clock frame 213 and the surrounding clock casing, not shown.

Pinion 229, attached to, or integral with key shaft 228, meshes with gear 221 which is fastened to shaft 220 to which is fastened also, cam 219 which is rotated through approximately one revolution when key shaft 228 rotates through its maximum number of revolutions or from full-wound to unwound condition of spring 227. Shaft 212 is bent to form arm 217 with a further bent arm 218 arranged to strike cam 219 and so to prevent hammer 231 from striking bell 232 until the cam has been rotated through a sufficient angle. When the cam is in the position shown in Figure 18 it does not interfere with movement of arm 217 and therefore will not limit the amplitude of vibration of hammer 231. Therefore if cam 219 is so fastened to shaft 220 that when spring 227 is fully wound, it prevents hammer 231 from striking bell 232 until it is rotated through a certain angle, the alarm will first begin, when released by the time gears, as a soft buzzing sound and then will become a loud alarm when hammer 231 strikes bell 232.

Figures 19, 20 and 21 show an alarm especially adapted to electric clocks. Line wire 251 is connected to magnetizing coil 233 through switch 252, wire 253, make-and-break contact 237, flexible vibrating arm 236 pivoted or mounted on frame 241 at 238, and through wire 239. The other line wire 250 may be connected to coil 233 through wire 242 and through resistance 244 or through resistance 244 in parallel with low resistance wires 243 and 242.

Cam 258 with low step 256 and high step 257 is attached to disc 259 which is rotatable on shaft 260 which carries hour hand 261. Spring 263 normally presses disc 259 against pointer 262 which is attached to shaft 260. Notches 265 are provided in the raised rim 266 of disc 259 so that disc 259 may be pressed in and turned so that it can be set with reference to the numbers on disc 259, which numbers represent hours. Therefore by setting disc 259 with reference to pointer 262 which drives disc 259, the position of cam 258 may be adjusted so that step 256 will strike lug 246 on flexible strip 245 at any time desired so that contact 247 on strip 245 and contact 248 on strip 249 will be brought together. When this happens, buzzer coil 233 will be energized with resistance 244 in series so that there will be a soft buzz. As hour hand shaft 260 rotates, however, high step 257 will then strike lug 246 and will press flexible strip 245 and 249 over until contact 254 on strip 249 touches contact 255 to which is connected wire 243. Then there

will be a direct connection of line 250 to coil 233 and the buzz will be very loud. The alarm will finally cease after cam 257 is rotated past lug 246 or it may be cut off by opening switch 252. While pointer 262 is shown as fitting into notches, a ratchet construction may be used. Disc 259 passes through back casing 264 of the clock.

Unnecessary detail has been largely eliminated in this description for the sake of clarity. For instance, in most cases the manual alarm release has not been shown but it should be understood that this feature would be incorporated as usual. Likewise the release operated by the time gears has not been shown in most cases since that is usual in all alarm clocks and is not necessary for a proper understanding of my improved variable alarms.

In Figure 22 hammer 267 is fastened to hammer arm 268 which is attached to verge 269 which is pivoted at 270 in usual manner. Toothed wheel 271 which actuates verge 269 is fastened to pinion 272 and both are fixed to shaft 273 which has bearing in the frame of the clock. Meshing with pinion 272 is gear 274 attached to key shaft 275 which is rotated by the alarm spring 276 when the alarm is released by the time gears; manual sliding lock 277 having been pulled back beforehand to remove lug 278 from wedge 279 which is attached to hammer arm 268.

Clutch plate 280 which has a frictional slip connection with shaft 275 has arm 281 attached to it and also arm 282. Now when locking rod 277 is pushed to the left so that lug 278 strikes wedge 279 to lock hammer arm 268, arm 283 which is integral with rod 277 will at the same time strike arm 282 and will rotate plate 280 and consequently arm 281 in counter clockwise direction until arm 282 strikes stop pin 284 attached to frame 285. In this position the alarm mechanism will be set for soft, slow signals since arm 286, pivoted to frame 285 at 287, will be pulled down by spring 289 so that valve 288 will close port 290 in cylinder 291 so that piston 292 will meet with back pressure when oscillated by rod 293 linking piston 292 to hammer arm 268. Therefore bell 294 will first be struck soft blows by hammer 267 at a slow rate. Then as spring shaft 275 is rotated, friction plate 280 will rotate arm 281 in clockwise direction until it strikes inclined surface 296 of bent arm 295, which is integral with pivoted lever 286, so that arm 295 will be forced down and valve 288 will be lifted to allow air to escape freely from cylinder 291. Therefore the rate of vibration of hammer 267 will speed up considerably, there being little back pressure to damp the movement. Arm 281 will rotate until it strikes stop lug 297 on arm 295. Then key shaft 275 will continue to rotate and vibrate hammer 267 since clutch 280 will slip; and the alarm will continue to produce loud signals at a fast rate until spring 276 is unwound, or until alarm lock 277 is pushed to the left to stop movement of the alarm mechanism and to set the alarm to soft signal position as previously described.

It will be seen therefore, that this alarm will always start with gentle signals and will then produce louder, faster signals after a period of time, regardless of whether the alarm spring is fully or partially wound.

While piston 292 is shown linked to the hammer arm 268, it is obvious that it can be linked to any of the alarm gears or other parts of the alarm mechanism.

In Figure 23 gear 298 is attached to spring 75

driven key shaft 299 and meshes with gear 300 fastened to shaft 301. Pivoted to gear 300 at 5 302 is link 303 to which is pivotally attached piston 304 which may be oscillated in cylinder 305, having valve 306 as before. Attached to link 303 is hammer arm 307 to which is preferably loosely fastened hammer 308 adapted to strike bell 309 when gear 300 is rotated. Valve 306 is 10 operated as previously described in Figure 22. This construction eliminates the toothed wheel.

In Figure 24, gong 310 is pivoted to the frame 313 at 311 so that it can be moved through an angle by moving arm 312 which is attached to gong 310 near its center. Lug 314 is fastened to 15 the outer rim of gong 310 and is not struck by vibrating hammer 315 when arm 312 is in the position shown, being held in place by spring operated catch 319 pivoted to frame 313 at 320. Catch 319 has lug 321 adapted to be struck by 20 pin 322 attached to clutch plate 323, which has slipping connection with key shaft 324, so that when this shaft is rotated under influence of its driving spring, pin 322 will be rotated in clockwise direction and will strike lug 321 on catch 25 319 and will release arm 312 so that it will be pulled up against stop lug 325 on frame 313. Tension spring 326, attached to arm 312 and frame 313 urges arm 312 in clockwise direction.

When arm 312 is resting against stop lug 325, 30 lug 314 is rotated so that hammer 315 will strike it so that the alarm will produce a loud signal. Alarm lock rod 327 is guided by bearings in frame 313, and arm 328, attached to rod 327, presses against toothed wheel 318 and locks it 35 when rod 327 is pushed down. When this is done the lower part of rod 327 pushes arm 312 down so that catch 319 will hold it in the position shown. One edge of rod 327 has rack teeth 329 which mesh with pinion 330 frictionally attached 40 to clutch plate 323 both of which are rotatable against friction on key shaft 324. When arm 328 is pulled up to unlock the alarm, rod 327 is pulled up sufficiently so that teeth 329 are out of mesh with pinion 330 so that the alarm mechanism 45 may be rotated freely. Stop lug 331 is pivoted to frame 313 so that it turns freely to allow pin 322 to pass when this pin rotates in clockwise direction but when rod 327 is pushed down to lock the alarm, rack teeth 329 mesh with pinion 330 and turn it and pin 322 in counter clockwise 50 direction until pin 322 strikes pivoted stop lug 331 which does not bend in this direction. Therefore each time the alarm is locked pin 322 will be set in the same position so that the alarm 55 will produce a buzz for a period before pin 322 strikes lug 321 and releases arm 312 to produce loud signals. Likewise each time the alarm is locked, rod 327 pushes arm 312 down so that it will be held by catch 319 for an initial soft alarm 60 period. Since pinion 330 is frictionally attached to clutch plate 323, rod 327 may be pushed down its full travel even though pin 322 may be forced against stop lug 331.

Hammer 315 is vibrated by hammer arm 318, 65 verge 317, toothed wheel 318, and associated gears 332, 333, 334 and 335 as usual.

Many variations of all these designs are easily possible and many combinations of the various constructions may be made without departing 70 from the essential principles involved.

What I claim is:

1. In an alarm device, a sound producing element, a hammer adapted to strike said sound

producing element, spring-driven means to actuate said hammer, and resisting means continuously causing a retarding effect upon said spring-driven means to cause slow vibration of said hammer until said retarding effect of said resisting means is automatically lessened by movement of said spring-driven means, to cause faster vibration of said hammer. 5

2. In an alarm device, a sound producing element, an oscillatory hammer arm carrying a hammer to strike said sound producing element, spring-driven means to actuate said hammer arm and said hammer, and resisting means acting upon said spring-driven means to cause said hammer arm to oscillate slowly so that said hammer will strike said sound producing element slowly at measured intervals until the resisting effect of said resisting means is automatically lessened by movement of said spring-driven means, to cause faster oscillations of said hammer arm and more rapid blows of said hammer upon said sound producing element. 10 15 20

3. In an alarm device, a sound producing element, an oscillatory hammer arm carrying a hammer to strike said sound producing element, a toothed wheel engaging said hammer arm to oscillate said arm, spring-driven means to rotate said toothed wheel, resisting means acting upon said spring-driven means to cause said hammer to strike said sound producing element slowly 25 until the resisting effect of said resisting means is automatically lessened by movement of said spring-driven means, so that said hammer will strike said sound producing element at a faster rate. 30 35

4. In an alarm device, a sound producing element, a hammer adapted to strike said sound producing element, hammer oscillating means, centrifugally operated means exerting a continuous braking effect upon said hammer oscillating means to cause slow strokes of said hammer upon said sound producing element, and means for automatically removing said braking effect so that said hammer will strike said sound producing element at a faster rate. 40 45

5. In an alarm device, a sound producing element, a hammer arm carrying a hammer to strike said sound producing element, a verge on said hammer arm, a rotatable toothed wheel engaging said verge on said hammer arm to vibrate said arm, means for rotating said toothed wheel, a centrifugal brake to cause slow rotation of said toothed wheel so that said hammer will strike said sound producing element at a slow rate, and means for automatically removing the effect of said brake so that said hammer will strike said sound producing element at a faster rate. 50 55

6. In an alarm device, a sound producing element, a hammer adapted to strike said sound producing element, hammer actuating means, means for creating a resisting effect in said hammer actuating means so that said hammer will strike said sound producing element slowly at intervals, said resisting effect being constantly in effect during each instant until said means for creating a resisting effect is automatically affected by movement of said hammer actuating means so that said resisting effect will be lessened with the result that said hammer will strike said sound producing element at a rapid rate. 60 65 70

ALBERT G. THOMAS.
